(57) **CLAIM**

The ornamental design for toy helicopter rotors, as illustrated and described.

DESCRIPTION

FIG. 1 is a front perspective view of the toy helicopter rotors in accordance with my design;

FIG. 2 is a rear perspective view of the toy helicopter rotors shown in FIG. 1;

FIG. 3 is a front view of the toy helicopter rotors shown in FIGS. 1-2;

FIG. 4 is a rear view of the toy helicopter rotors shown in FIGS. 1-3;

FIG. 5 is a left side view of the toy helicopter rotors shown in FIGS. 1-4;

FIG. 6 is a right side view of the toy helicopter rotors shown in FIGS. 1-5;

FIG. 7 is a top view of the toy helicopter rotors shown in FIGS. 1-6; and,

FIG. 8 is a bottom view of the toy helicopter rotors shown in FIGS. 1-7.

The broken lines are included for the purpose of illustrating portions of the toy helicopter that form no part of the claimed design.

1 Claim, 7 Drawing Sheets
